UNITED STATES PATENT OFFICE.

HERNAN CORTES CHAPMAN, OF LEAMINGTON, ONTARIO, CANADA.

HEADLIGHT DIMMER.

Application filed January 30, 1922. Serial No. 532,870.

To all whom it may concern:

Be it known that I, HERNAN CORTES CHAPMAN, a citizen of the United States of America, residing at Leamington, in the 5 Province of Ontario and the Dominion of Canada, have invented certain new and useful Improvements in Headlight Dimmers, of which the following is a specification, reference being had therein to the accompanying drawings.

The invention relates to light dimmers and refers particularly to dimmers for use in motor vehicle headlights. The invention has for one of its objects the provision of a 15 simple construction of dimmer which may be readily applied and which will permit of removal and replacement of the light bulb. The invention also has for one of its objects the provision of a dimmer having adjustable shields which may be adjusted to 20 suit different driving conditions. Further objects of the invention reside in the novel features of construction and combinations and arrangements of parts as more fully 25 hereinafter set forth.

In the drawings:

Figure 1 is a central cross section through a headlight with a dimmer embodying my invention applied;

30 Figure 2 is a side elevation partly in section of the dimmer;

Figures 3 and 4 are respectively front and rear elevations thereof.

As shown in Figure 1, 1 is the reflector of 35 a headlight, 2 the glass, and 3 the bulb. 4 is the dimmer attachment having a frame which comprises the front and rear rings 5 and 6 respectively connected by the tie bars 7. The rear ring has the arms 8 leading to 40 the socket 9 which fits over the socket 10 detachably carrying the bulb 3, this bulb having on its supporting base the diametrically opposite pins or projections 11 adapted to engage in the bayonet slots 12 in the socket 10. The 45 socket 9 of the dimmer frame is detachably secured to the socket 10 in the same manner. In detail, 13 are diametrically opposite pins or projections extending inwardly from the socket 9 and detachably engaging in bayonet 50 slots in the socket 10.

55 14 and 15 are segmental colored glass shields upon one side of the bulb 3 and extending between the front and rear rings 5 and 6 respectively, and carried thereby. The shield 14 is stationary, while the shield 15 is rotatable with its axis of rotation register-

ing substantially with the longitudinal axis of the bulb 3. The radius of the shield 15 is less than that of the shield 14 so that the two may be arranged in nested relation 60 above the bulb 3. Also, the arcs of the shields are sufficient so that when the adjustable shield 15 is rotated to its lowermost position as indicated by the dotted line 16 in Figure 2, there is formed in effect, a cylindrical shield surrounding the bulb 3. 17 and 18 are relatively adjustable semi-circular colored glass shields carried by the front ring 5 and arranged in front of the bulb 3. The shield 17 is stationary, while the shield 70 18 may be rotated with its axis of rotation substantially registering with the longitudinal axis of the bulb 3 so that the two shields may form, in effect, a circular shield in front of the bulb 3 or they may be made 75 to register with each other, in which case, the upper half, substantially, of the bulb 3 will be shielded. The rotatable segmental shield 15 is held in its positions of adjustment by suitable means such as the set screws 80 19 in the tie bars 7 while the rotatable shield 18 is held in its positions of adjustment by the screw 20.

For the purpose of providing for ventilation when the shields 15 and 18 are adjusted 85 to closed positions the apertures 21 are provided near the top of the front ring 5.

To permit of ready removal and replacement of the bulb 3, the front ring 5 is detachably connected to the rear ring 6 of the 90 dimmer frame by the pins 22 at the front ends of the tie bars 7.

With the above construction, the shield 18 may be adjusted to completely shield the front of the bulb 3 and the shield 15 may 95 also be adjusted so that the bulb will be completely surrounded, so that with the shields, which are preferably blue, in these positions all light passing from the headlight will be soft. The bright light passing 100 rearwardly from the bulb strikes the reflector of the headlight and then passes the dimmer and commingles with the colored light passing through the shields. As a result of this commingling of bright and very 105 soft colored lights, a soft light suitable for city driving or the like is secured. However, for country driving, the front shield 18 may be rotated to register with the front shield 17 and the side segmental shield 15 may be 110 rotated to nest with the side segmental shield 14 so that a greater amount of bright light

is permitted to strike the reflector, but this bright light strikes that portion of the reflector which will not raise the same into the eyes of the driver of an oncoming motor vehicle. The light passing above the longitudinal axis of the bulb remains soft. Thus with this arrangement of shields, the road ahead of the motor vehicle can be illuminated for a greater distance without producing an objectionable glare.

What I claim as my invention is:

1. The combination with a light bulb, of a dimmer comprising substantially parallel rings, a tie bar therebetween, relatively adjustable segmental shields extending between said rings and arranged at the side of said bulb, and a shield carried by one of said rings and arranged in front of said bulb.
2. The combination with a light bulb and a socket detachably carrying said bulb, of a dimmer detachably mounted upon said socket and comprising substantially parallel rings of greater diameter than said bulb and arranged at the ends thereof, a tie bar detachably connecting said rings to each other, relatively adjustable segmental shields extending between said rings and carried thereby, and relatively adjustable shields carried by one of said rings at the front of said bulb.
3. The combination with a reflector, a socket extending therethrough, and a light bulb detachably carried by said socket, of a dimmer detachably carried by said socket comprising a frame, relatively rotatable segmental colored shields carried by said frame at the side of said bulb, and relatively rotatable colored shields also carried by said frame and arranged in front of said bulb.
4. The combination with a light bulb, of a dimmer comprising a pair of shields at one side of said bulb, one of said shields being adjustable, and a pair of shields in front of said bulb, one of the last mentioned shields being adjustable independently of the adjustable shield aforesaid.
5. The combination with a light bulb, of a dimmer comprising a pair of segmental shields at one side of said bulb, one of said shields being adjustable, and a pair of semi-circular shields in front of said bulb, one of said semi-circular shields being adjustable independently of the adjustable segmental shield aforesaid.

6. The combination with a reflector, a socket extending therethrough, and a light bulb detachably carried by said socket, of a dimmer comprising a frame including front and rear rings, and tie-bars connecting said rings, means for removably securing the rear ring to said socket, colored shields carried by said frame at the side of said light, one of said shields being adjustable, and means for retaining said adjustable shield in adjusted position.

7. The combination with a reflector, a socket extending therethrough, and a light bulb detachably carried by said socket, of a dimmer comprising a frame including front and rear rings and tie bars connecting said rings, means for removably securing the rear ring to said socket, colored shields carried by said frame at the side of said light, one of said shields being adjustable, means for retaining said adjustable shield in adjusted position, and relatively adjustable colored shields carried by the front ring and arranged in front of said bulb.

8. The combination with a reflector, a socket extending therethrough, and a light bulb detachably carried by said socket, of a dimmer detachably carried by said socket comprising a frame including a pair of spaced rings, one of said rings having apertures formed therein, segmental colored shields carried by said frame between said rings and arranged upon one side of said bulb, one of said shields being adjustable, means for retaining said adjustable shield in adjusted position and relatively adjustable, semi-circular colored shields carried by one of said rings and arranged in front of said bulb.

In testimony whereof I affix my signature.

HERNAN CORTES CHAPMAN.
